UNITED STATES PATENT OFFICE.

GEORGE H. POOR, OF CHICAGO, ILLINOIS, ASSIGNOR TO SAMUEL WORTHINGTON McMUNN, OF CHICAGO, ILLINOIS.

CONCRETE PILE.

SPECIFICATION forming part of Letters Patent No. 770,475, dated September 20, 1904.

Application filed January 28, 1904. Serial No. 190,982. (No model.)

To all whom it may concern:

Be it known that I, GEORGE H. POOR, a citizen of the United States, and a resident of Chicago, in the county of Cook and State of Illinois, have invented certain new and useful Improvements in Concrete Piles; and I do hereby declare that the following is a full, clear, and exact description thereof, reference being had to the accompanying drawings, and to the letters of reference marked thereon, which form a part of this specification.

This invention relates to an improved construction in concrete piling for use in making retaining-walls, foundations, and the like, the invention relating more particularly to piling of that class which is sunk into the earth by the ejection of jets or streams of water from the lower ends of said piles, by which the earth around the lower ends of the piles is loosened or displaced and the same allowed to sink.

A pile embodying my invention consists of a mass or body of concrete, the upper part of which is of elongated or slab form and constitutes the main or body portion of the pile and the lower part of which consists of a plurality of parallel prongs or projections which extend downwardly from the lower edge of the body and each of which is provided with a separate water-supply pipe terminating at the lower end of the projection in which it is located and from which water may be ejected at the lower end of each projection, so as to permit the entire pile to sink into the earth.

As shown in the accompanying drawings, Figure 1 is a view, partly in side elevation and partly in central vertical section, of two adjacent piles embodying my invention. Fig. 2 is a plan section thereof, taken upon line 2-2 of Fig. 1. Fig. 3 is an edge elevation of one of the piles. Fig. 4 is an enlarged detail section of the lower end of one of the prongs or projections on the pile.

As shown in the said drawings, A indicates the body of a pile embodying my invention, and *a a a a* four prongs or downwardly-projecting extensions thereof, said body and its prongs being made of an integral mass of concrete. Said prongs or projections *a a a a* are

shown as tapered from their upper toward 50 their lower ends and as having their upper ends where they join the body part of the pile as large as the thickness of said body part. Said prongs or projections are, moreover, shown as arranged closely adjacent to each 55 other at their upper ends; but this particular arrangement is immaterial, as they may be spaced at a greater or less distance apart, as may be found desirable or preferable in any particular instance. The tapered form of the 60 said prongs or projections constitutes an important feature of my invention and affords advantages in the use of the pile, which will be hereinafter pointed out.

B B indicate water-pipes which are embedded in and extend longitudinally through the prongs or extensions *a a*. Each of said prongs or extensions will be provided with one of said water-pipes, so that in a pile like that shown having four of said prongs or extensions four 70 water-pipes will be used. The water-pipes are embedded in the cement during the process of molding the pile and serve to give strength to the said prongs additional to that afforded by the concrete itself. This is a matter of considerable importance, because for the best results the prongs are made of considerable length in proportion to their cross-sectional area and are considerably tapered, so that their extreme ends or points would 80 have little strength in the absence of the support afforded by the said pipes.

The body part A is preferably made somewhat wider than the combined widths of the four prongs *a a a a* or, in other words, is arranged to extend laterally beyond the outermost of the said prongs, so as to form shoulders, as indicated at *a'*. These shoulders are preferably provided with downwardly-converging side faces, giving an annular form to 90 the said shoulders, as clearly seen in Fig. 3. The making of the body part of the pile wider than the combined widths of the upper ends of the prongs is for the purpose of facilitating the joining of the side margins of the body 95 portions of two adjacent piles and to enable such body portions to better form a retaining-wall. It is not, however, necessary that the

body of the piles project beyond the prongs or projections nearest said side edges, and the prongs may be spaced so wide apart or such number of them may be used as to bring the 5 exterior prongs at the side edges of the body part, it being necessary only that the said prongs or projections should be sufficient in number and so closely spaced on the lower-edge margin of the body of the pile as to enable the pile as a whole to be sunk into the earth by water ejected from the lower ends of the several prongs or projections. The prongs or projections are shown in the drawings as being made of rectangular form in 15 cross-section, this form thereof being preferred, because it facilitates the molding of the pile in a horizontal open-topped form or mold. Said prongs may, however, be made of round or other form in cross-section.

20 The body part A of the pile may be either solid or hollow. As a preferable construction and as herein shown, it is provided with two recesses a^2 , which serve to lessen the weight of the pile and to thereby facilitate the handling thereof during the driving or sinking operation. After the pile has been set such recesses may be filled with earth or cement, as indicated at A' in the drawings. The side portions of the body part of the piles may, 25 moreover, be strengthened by pieces C C of woven wire or interlaced metal rods inserted therein in molding, and like pieces C' C' of woven wire may be inserted in the prongs or projections a^a . Such pieces C' C' when used 30 will preferably extend from the projections upwardly into the body part of the pile, so as to strengthen the connections between these parts.

The pipes B B are shown as connected at 40 their upper ends with supply-pipes B' B' by means of detachable joints b^b . Said supply-pipes are shown as extended downwardly through the recesses in the pile, and the joints b^b as located near the bottoms of the recesses 45 a^a . Said joints enable the supply-pipes B' B' to be disconnected from the lower pipes B B, which are embedded in the prongs after the piles have been set, thereby enabling the pipes B B to be made short and the cost of 50 longer pipes to be saved, the supply-pipes B' B' being of course used continuously for any number of piles. The drawings show separate nozzles B² as applied to the lower ends of the pipes B, these nozzles being tapered downwardly and affording exits for water smaller than the bore of the pipes to give greater force to the jets of water that are ejected from the lower ends of the prongs.

Several of the wide and thin piles made as 60 described may be set up edge to edge and will by themselves form a complete retaining-wall, or they may form the foundation for a retaining-wall built above them, or they may constitute the foundation of the wall of a building or other structure. Preferably the body

portions of the piles will be provided at their side edges with interlocking parts—such, for instance, as the tongues a^3 and grooves a^4 shown in Fig. 2.

The provision of the downwardly-extending 70 prongs or projections having the general form of separate piles on the lower margins of the body parts A of the pile have the advantage of greatly increasing the load-sustaining capacity of the pile or its capacity to withstand 75 weight or downward stress applied to its upper edge. Such augmented capacity to resist downward pressure is due to the extended frictional surface for contact with the surrounding soil or earth afforded by the said prongs 80 or projections. Moreover, as the soil immediately surrounding the lower end or point of each projection only is moved or shifted by the action of the current of water ejected from the lower ends of the prongs or projections 85 the soil between the prongs or projections remains largely undisturbed in the sinking operation, and thus tends to hold the pile firmly in place and prevent either lateral movement thereof or further sinking under the load to 90 which the pile as a whole is subjected.

A special advantage is obtained by making the prongs or extensions a^a of downwardly-tapered form, not only because of the increased surface area thus afforded for frictional contact with the earth, but because of the wedging action of said tapered projections tending to resist further downward movement of the piles in the surrounding earth after they have been sunk by the use of the water-jets, it being obvious that after the pile has been sunk and the soil has settled around the prongs the latter when tapered cannot sink further except by displacing laterally the soil immediately surrounding them, which in 105 most circumstances is rendered impossible by reason of the compactness or resistance to compression of the soil.

I claim as my invention—

1. A concrete pile consisting of a body portion of laterally-elongated or slab form having a plurality of extensions or prongs projecting downwardly from its lower edge. 110
2. A concrete pile consisting of a body portion of laterally-elongated or slab form having a plurality of downwardly-tapered extensions or prongs on its lower edge. 115
3. A concrete pile consisting of a body portion of laterally-elongated or slab form having a plurality of extensions or prongs projecting from its lower edge, and water-pipes extending through said prongs. 120
4. A concrete pile consisting of a body portion of laterally-elongated or slab form, having a plurality of extensions or prongs projecting from its lower edge, said body portions of the pile being hollow. 125
5. A concrete pile consisting of a body portion of laterally-elongated or slab form having a plurality of extensions or prongs projecting 130

from its lower edge, said body portion being provided with a recess which opens through the upper edge of the pile, and which may be filled after the pile is set.

5 6. A concrete pile consisting of a body portion of laterally-elongated or slab form having a plurality of extensions or prongs on its lower edge, and water-pipes which are embedded permanently in the said extensions or prongs
10 and which are adapted for connection with

supply-pipes that extend downwardly within the body part of the pile.

In testimony that I claim the foregoing as my invention I affix my signature, in presence of two witnesses, this 16th day of January, 15
A. D. 1904.
